METHOD AND DEVICE FOR DETERMINING THE EXPANSION LINE OF STEAM TURBINES.

Application filed March 9, 1925, Serial No. 14,028, and in Austria May 6, 1924.

This invention relates to steam turbines and particularly to a measuring method and device for steam turbines, by which working conditions of the turbine may be determined 5 at any stage or phase of the turbine and its operation by measuring the heat contents.

The main object of the invention is to avoid disturbances and interruptions in the operation of the turbine while testing the 10 steam consumption,—to find out the conditions prevailing at any stage of the turbine, and to determine stages which do not work properly.

While in the piston engine it is easy to determine 15 with the indicator the working of the engine, it is not so easy with the steam turbine because the transformation of the energy of the steam is too complicated. Between these engines is a basic difference: In 20 the piston engine, the expansion of the steam is used directly by acting upon the piston, and this process or method is indicated easily by the indicator. But in the steam turbine, the transformation of the steam 25 energy into work is made indirectly by transforming the pressure into velocity. This process cannot be determined with the known indicator.

The mechanical work of a steam turbine 30 is usually indicated in the entropy diagram and marked by the distance of the real expansion line from the adiabatic line. In the entropy diagram it is possible to indicate how much work has been done and thus it 35 shows exactly the working of the engine. The individual points of the expansion line could be determined by indicating the pressure and the temperature in the superheated zone. The steam flow in a turbine, however, 40 interferes with the pressure and temperature measurement methods, so that great difficulties arise in these measurements. Therefore, it is not possible to determine exactly the expansion line and to provide an instrument 45 corresponding to the indicator of the reciprocating steam engine.

However, nothing would be more desirable for the examination of the steam turbine than a device which would make it possible 50 to examine or test the steam turbine at any time and during its operation, without the expensive and work-disturbing steam consumption tests. As the turbine consists of several stages, it is above all desirable to 55 know whether all of the stages work perfectly, or what stage does not work well.

Only then, when this is found out, is it possible to examine the turbine exactly.

The invention principally consists in a method and in a measuring apparatus, by 60 which it is made easy to measure, at any time and in any stage, the heat contents, whereby it is made possible to judge the conditions existing in the turbine at any stage, and the 65 working of the whole engine.

The method is based upon the determination of the heat contents of the steam in any stage of the turbine.

One embodiment of the invention is illustrated in the accompanying drawing, which 70 shows diagrammatically a turbine equipped with the necessary apparatus for making the tests and measurements.

In the embodiment illustrated diagrammatically in the drawing *n* is a turbine and *h* a connection or pipe line including a valve *f* therein leading from the turbine to the measuring and testing apparatus. The pipe line *h* connects the stage or point of the turbine which is to be tested, for instance, as indicated at the point *x*. This connection may be made at any suitable point or stage of the turbine. Through the pipe *h*, the steam flows to the measuring and testing apparatus. During the tests, the points and 80 stages to be tested may be connected, one after the other, through pipe *h*, with the testing apparatus. The connections may be made or disconnected in any suitable way. The connection of the pipe *h* with the individual turbine points, may be a shiftable or travelling device, or the individual testing points of the turbine may be connected with the main line *h* by branches *q*, with valves *p* therein, so that, by closing or opening one 85 of the valves *p*, any selected point of the turbine may be connected with or disconnected from the testing apparatus. Of course, each testing point or stage of the turbine could be equipped with pipe connections *q* and valves *p* for connection with the main line *h*, and, in certain cases, when all of the branch lines *q* between the pipe line *h* and the different turbine points are provided with valves *p*, the valve *f* in the line *h* may be 90 disposed of.

The measuring and testing apparatus proper, as indicated diagrammatically in the drawing, comprises a gauged container *a* for the cooling water used in the test for condensing the steam and measuring the heat units absorbed from the steam.

The container *a* is connected by discharge pipe *i*, controlled by a valve *e*, with a small surface condenser *b*, which is also connected with the pipe *h*, carrying the steam to be condensed from the turbine *n*.

For measuring the pressure and temperature of the steam, suitable gauges may be provided.

The surface condenser is connected through 10 pipe *r* with a gauged water receptacle *c*, into which the cooling water is discharged. In certain cases, a valve (not shown) could be provided in the discharge pipe *r*. The condensate is passed through pipe *h* and valve *g* 15 form the surface condenser into a gauged receptacle *d*. The valves *e*, *f* and *g* are shut-off valves.

The measuring apparatus illustrated operates as follows: It is assumed that the stage 20 or point *x* of the turbine, which is connected with pipe line *h*, is to be tested, (measured). The shut-off valves *e*, *f* and *g* are now open. The steam flows out of the stage *x* through the pipe line *h* into the condenser *b*, is here 25 condensed, and the condensate enters into the receptacle *d* which is connected with the main condenser (not shown) of the turbine by the pipe line *l*, or, when there is a back pressure turbine, it may be connected with the exhaust, or with the same point to 30 which the exhaust line *s* leads. The cooling water flows from the receptacle *a* through the condenser *b* into the receptacle *c*. As these two receptacles are gauged, it is possible to determine the cooling water consumption during the test simply by reading off or measuring; and it is just as easy to 35 measure the temperature *t*₁ in the receptacle *a* and *t*₂ in the receptacle *c*. Hence, the heat quantity absorbed from the cooling water, is *W* · (*t*₂ - *t*₁) *w* designating the 40 quantity of the water passed through the condenser during the test and *t*₁, *t*₂, the temperatures in the receptacles *a* and *c* respectively, as indicated in the drawing. On 45 the other hand, the steam-quantity passing through the condenser is measured by simply reading off in the gauged collector *d* for the condensate, which may be for instance 50 D kilograms, and in the same collector the temperature *t*₃ of the condensate, which indicates its heat contents. Then the heat contained in the steam before the entrance 55 into the apparatus may be calculated according to following equation

$$\frac{(\mathbf{t}_2 - \mathbf{t}_1) \cdot \mathbf{W} + \mathbf{D} \cdot \mathbf{t}_3}{\mathbf{D}} = \mathbf{J};$$

in which *J* designates the heat contents to be calculated. *t*₁', *t*₂' and *t*₃' indicate thermometers for measuring the temperatures *t*₁, *t*₂ and *t*₃ of the water in the receptacles *a*, *c* and *d* respectively. The apparatus may be so arranged that the collectors *c* and *d* 65 are put on scales which show automatically

the quantities contained in the corresponding receptacles. *V* may indicate the platforms or a part of such scales. The manometer *m* in the pipe line *h* shows the pressure in the tested stage, so that the corresponding point in the so-called JS diagram (Mollier or entropy diagram), is exactly determined. This measurement can be made for every stage of the turbine, as indicated by dotted lines *o* in Fig. 1, and by full lines *g* and valves *p* in the left side of Fig. 1, and the entirety of the points determined by the tests shows in the JS diagram an exact picture of the working condition of the turbine. The device of the invention makes it possible to judge correctly the work of the turbine and has the advantage that these tests may be made without disturbing the normal work of the turbine. The apparatus may be made of such dimensions that it can be transported easily to the place where the tests are to be made.

In certain cases, it is preferable to measure 90 also the steam temperature of the extracted steam, and to provide means (not shown) for measuring this temperature (for instance, thermometers) particularly for checking.

The tests can be made with a predetermined quantity of cooling water during predetermined intervals of time. The apparatus may be carefully insulated against heat radiation, which will make the results still more exact, and which will facilitate the compilation of charts and tables for simply reading the results.

It should be understood that the present embodiment of the invention is merely illustrative and that many modifications in the arrangement of the apparatus and in the details of the parts will suggest themselves to those skilled in the art, according to changed conditions and requirements, within the scope of this invention as defined by the appended claims.

Having thus described my invention, I claim:

1. Method for determining the expansion line of steam turbines comprising measuring the heat-contents of the steam of individual stages of the turbines by extracting steam from said individual stages and measuring its pressure, condensing said steam with cooling water, measuring the temperature and weight (quantity) of the condensate of said steam and measuring the temperature and weight or quantity of said cooling water before and after condensing said steam.

2. Method for determining the expansion line of steam turbines, comprising measuring the heat-contents of the steam of individual stages of the turbine by extracting steam from said individual stages and meas-

- uring its pressure, condensing said steam with cooling water and measuring the temperature and weight or quantity of the condensate of said steam and measuring the 5 temperature and weight or quantity of said cooling water before and after condensing said steam and measuring also further the temperature of the steam extracted from said individual stages.
- 10 3. A device for measuring and testing the working conditions of a turbine, comprising in combination a surface condenser which is connected on the one hand with the stage of the turbine and on the other hand with a 15 gauged receptacle for collecting the condensate, a gauged receptacle for collecting the cooling water passed through the condenser, and means for measuring the temperature of the condensate and of the cooling 20 water.
4. A device for determining the expansion line of steam turbines, comprising in combination a surface condenser, means for connecting the condenser with the stages 25 of the turbine, a gauged receptacle for collecting the condensate, means for measuring the quantity of the cooling water used for condensing and passed through the condenser, and means for measuring the temperature 30 of the condensate and for measuring the temperature of the cooling water before and after condensing.
5. A device for determining the expansion line of steam turbines, comprising in combination a surface condenser, means for connecting said condenser with the stages of the turbine, a gauged receptacle for collecting the condensate, a gauged receptacle for feeding the condenser with cooling water, a 35 gauged receptacle for collecting said cooling water from said condenser, and means for measuring the temperature of the condensate and means for measuring the temperature of the cooling water before and after condensing.
- 40 6. A device for determining the expansion line of steam turbines, comprising in combination a surface condenser, means for connecting said condenser with the stages of the turbine, a gauged receptacle for collecting the condensate, a gauged receptacle for feeding the condenser with cooling water, a 45 gauged receptacle for collecting said cooling water from said condenser, and means for measuring the temperature of the condensate and means for measuring the temperature of the cooling water before and after condensing.
- 50 7. A device for determining the expansion line of steam turbines, comprising in combination a surface condenser, a pipe line for connecting the condenser with the stages of the turbine, a gauged receptacle for collecting the condensate, a gauged receptacle for feeding the condenser with cooling water, a 55 gauged receptacle for collecting said cooling water from said condenser, and means for measuring the temperature of the condensate and of the cooling water before and after condensing, said gauged receptacle for collecting the condensate having a connection line leading to the main condenser or exhaust of the turbine.
- 60 8. A device for determining the expansion line of a steam turbine, comprising in combination a steam turbine, comprising in combination a surface condenser, means for connecting said condenser with the stages of the turbine, a 65 gauged receptacle for collecting the condensate, a gauged receptacle for feeding the condenser with cooling water, a gauged receptacle for collecting the condensate from said condenser and determining its quantity, a 70 gauged receptacle for feeding the condenser with cooling water, a gauged receptacle for collecting said cooling water from said condenser and determining its quantity, and means for measuring the temperature of the condensate and of the cooling water before and after condensing, said gauged receptacle for collecting the condensate having a connection line leading to the exhaust of the turbine or to the same point as the 75 exhaust for instance to the main condenser.
- 90 8. A device for determining the expansion line of a steam turbine, comprising in combination a surface condenser, means for connecting said condenser with the stages of the turbine, a manometer or gauge in said connection means, a receptacle for collecting the condensate, a receptacle for feeding the condenser with cooling water, a receptacle for collecting said cooling water, and means for weighing said collecting receptacles and their contents for indicating automatically the contents of said receptacles, and means, such as thermometers, for measuring the 95 temperature of the condensate and of the cooling water before and after condensing.
- 95 9. A device for determining the expansion line of multistage turbines, comprising in combination a condenser, a pipe-line for connecting the condenser with the turbine, said pipe-line having valve-controlled connection with the individual stages of the turbine, a gauged receptacle for collecting the condensate, a gauged receptacle for collecting the cooling water, means for measuring the 100 quantity of the condensate and cooling water, and means for measuring the temperature of the condensate and of the cooling water before and after condensing.
- 100 10. A device for determining the expansion line of a steam turbine, comprising in combination a condenser, a receptacle for cooling fluid, a receptacle for cooling fluid discharged from the condenser, a connection with the condenser attachable to the turbine stages to be tested and having means for measuring the temperature and pressure of the steam, a collecting receptacle for condensed steam connected with said condenser and with the condensing plant of the turbine, means for determining the temperature of the condensate and of the cooling water before and after condensing and means for measuring the quantity of the condensate and cooling water collected in 105 said collecting receptacle.
- 110 11. In a multistage turbine, in combination, means for extracting steam in small quantities from the stages of the turbine for measuring and recording purposes, means for 115
- 120
- 125
- 130
- 135

measuring the temperature and pressure of the extracted steam, a condenser for condensing the steam extracted from the stages of the turbine, means for collecting and measuring the cooling water passed through the condenser and for determining the temperature before and after condensing means for collecting and measuring the condensate from the condenser and for determining the 10 temperature of the condensate, and means for connecting and disconnecting the parts comprised in this combination.

12. In a multistage turbine, the combination of controllable tapping means for ex-

tracting steam at various stages of the turbine, for measuring and recording purposes, with condensing means, gauges arranged between the turbine and the condensing means for measuring and recording the temperature and pressure of the extracted steam, means 15 for measuring the temperature of the cooling fluid before and after condensing and for determining the quantity of cooling fluid used, and means for collecting the condensate and for measuring the quantity and 20 temperature thereof.

In testimony whereof I affix my signature.

FRANZ LÖSEL.
